UNITED STATES PATENT OFFICE

FREDERICK D. W. SEARING, OF NEWARK, NEW JERSEY

STABILIZING DEVICE

Application filed July 26, 1929. Serial No. 381,135.

The primary object of this invention is to enable ocean travelers to avoid sea sickness by furnishing for their use deck chairs, couches, beds and other pieces of furniture so supported that the piece of furniture does not partake of the rolling and pitching motions of the boat.

In its preferred form the object of the invention is to make a swing chair of an ordinary steamer deck chair thereby increasing its comfort for travelers.

The supporting structure in the preferred form comprises a system of levers preferably fulcrumed on axes disposed crosswise of the supporting standard and longitudinally of it. In the illustrated example the main supporting lever is pivoted in the line of the center of gravity of a person occupying the chair, the lever extending in a direction forwardly and backwardly of the occupant. A pair of cross levers attached to the chair preferably by straps or tapes are pivoted to the respective ends of the main lever. Retarding, dampening and cushioning means are preferably associated with the levers.

In the accompanying drawings a preferred form of my invention is shown for the purpose of illustration, in which drawings

Figure 1 shows in side elevation a form of my supporting device and a chair supported thereby.

Fig. 2 is a front elevation, and

Fig. 3 is a top view in the Fig. 2 position.

While this present invention does not exclusively pertain to the support of chairs, yet it is so peculiarly adapted for that purpose and especially for stabilizing chairs on deck that such use has been chosen for the purpose of illustration and description. A steamer chair of well known form is shown in the drawings having on each side a seat and leg member 5, a back and leg member 6, a brace 7 connecting the leg portion of member 6 to the foot rest 8, and an arm 9. When a deck chair is suspended from the supporting de-

vice a portable knockdown frame work, preferably made of wood, is desirable, such a frame work being shown and comprising four legs 10 adapted to stand upon the deck, and sloping inwardly toward their upper ends, 50 the pair at each side being connected by upper and lower braces 11, 12 and the lower braces 12, 12 being connected by two cross braces 13, 13 removably held in position in some suitable or well known manner, as for instance pins 14. An open box-like head is mounted on top of the legs 10, it having bottom pieces 15, top pieces 16, uprights 17 and cross pieces 18, 19 at the bottom and top. The pair of legs 10 at each side are shown 60 connected to the uprights 17 of the head by means of hinges 20 to facilitate folding for storage or for shifting about from place to place. Metal straps 200 are shown pivoted to the head rail 15 and removably bolted to 65 the legs for steadyng the structure.

My supporting device is herein illustrated mounted on top of this head, the chair suspended from it, and comprising a main lever 21 extending in a front to rear direction is fulcrumed on a pivot 22 seated in a wooden block 23 carried by a board 24 resting on top of the head structure. The pivot 22 is furnished with a thumb nut 25, between which and the lever a friction or tension device 26 70 of suitable construction is interposed. A pair of cross levers 27 are fulcrumed on pivots 28 to the dependent ends 29 of the lever 21. These pivots are also provided with thumb nuts 250 and tension devices 260. 80 It is upon these levers that the chair is supported. The cross levers 27 are, in the illustration, formed with dependent ends 30 to which flexible suspension straps 31 which are connected to the chair are attached. Eye bolts 32 are carried by the lever ends 30 for the engagement of ready releasing means carried by the straps, snap hooks 33 being shown. The lower ends of the rear straps 31 are shown attached to the seat and leg 90

members 5 and passing through guides 34 provided on the sides of the back and leg members 6. The lower ends of the front straps are attached to the foot portion 7 and 5 pass through guides 35 provided at the front ends of the leg and seat members 5.

It will be noted, particularly by having reference to Figure 1, that the guides 34 and 35 are so located that they bend the straps 10 31 forwardly.

As an additional supporting and steadyng means a strap 41 is shown connected to each of the front straps 31 preferably by engagement with the back of the buckle 42. The 15 lower end of this strap 41 is shown connected at 43 to the seat and leg member 5. The strap preferably passes inside the arm 9 and is also given a forward bend by means of a guide 44.

20 The location of the points of engagement of the straps 31 and 41 with the chair frame, and the points of engagement of the guides 34, 35 and 44 with the straps, is dependent largely upon the character of the service to 25 which the device is to be put including the weight of the load which it is to carry.

From the foregoing it will be quite obvious that, when the structure is set up on the deck of a boat, the weight of an occupant in the 30 chair causes this, through my system of levers, to maintain a stable position during the rocking of the boat at sea. According to one mode of proportioning and adjusting the parts, my device transforms the rolling and 35 pitching of the boat into a slow level swinging of the chair.

For certain sea caused boat motions the 40 free self-adjusting movements of the support are adequate to afford complete stabilization. There are, however, certain other well 45 recognized boat movements which from their suddenness in some instances and from their repetition or reversal in other instances require that the tilting of the levers be resisted and restrained, and that means also be provided for restoring them to their normal 50 positions. And also that spring means be provided for dampening the relative movement between the standard and the chair.

55 The movement of the lever 21 is controlled in this regard in the illustration by the adjustable friction device 26 and the extension springs 36 and 37. Preferably the front arm of the lever 21 is slightly shorter than is the rear end. The spring 36 connected to the rear arm of the lever is also preferably stronger or stiffer than is the spring 37 attached to the front end.

The movement of each of the levers 27 is 60 controlled by the friction devices 260 and the extension springs 38. The upper ends of the springs 38 for each lever 27 are attached to an eye bolt 39 upstanding from the upper side of the end of the lever 21. A centrally 65 disposed spring 45 is connected to one of the

cross bars 13 and to the under-part of the chair seat.

It is to be understood that changes in details of construction may be made within the scope of the claims without departing from 70 the spirit of my invention.

Having described my invention, I claim and desire to secure by Letters Patent:

1. In a steamer deck chair, the combination with legs adapted to rest upon the deck and furnished with a head piece, of a support upstanding from the head piece, a main lever pivoted to such support and having dependent ends, a cross lever pivoted to each end of the main lever below its pivot, the cross levers having dependent ends, an upstanding post at each end of the main lever, and having at its upper end means for the attachment of springs, and a pair of coiled extension springs attached to such means and to the dependent ends of the cross levers, and a chair suspended from the ends of the cross levers.

2. In a steamer deck chair, the combination with a frame work embodying legs for resting upon the deck, of a head piece, a standard carried by the head piece, a main lever fulcrumed on the standard, a cross lever fulcrumed at each end of the main lever and disposed transversely of it, a chair suspended by flexible straps from the ends of the cross levers, such chair being furnished with arms and flexible straps attached to the cross levers and to the fronts of the arms.

3. In a steamer deck chair, the combination with a frame work embodying legs for resting upon the deck, of a head piece, a block carried by the head piece, a main lever fulcrumed on the block, a lever fulcrumed at each end of the main lever and disposed transversely of it, a chair and flexible straps suspending the chair from the ends of the cross levers.

4. In a steamer deck chair, the combination with a frame work embodying legs for resting upon the deck, of a head piece, a block carried by the head piece, a main lever fulcrumed on the block, a cross lever fulcrumed at each end of the main lever and disposed transversely of it, a chair and flexible straps suspending the chair from the ends of the transverse cross levers, and springs associated with the standards and the chair for dampening the relative movements between the standards and the chair.

5. The combination with a frame work, of a main lever fulcrumed thereon, a lever fulcrumed at each end of the main lever and disposed transversely of it, flexible straps dependent from the ends of the transverse levers, and an article of furniture suspended on the straps.

6. The combination with a steamer deck chair, of a suspension device therefor, and flexible straps suspending the chair from the

suspension device such straps being connected to the lower portions of the chair, and crossing upper portions of the chair, there being guides carried by the chair at such upper portions for bending the straps and shortening the free length of strap.

5 7. The combination with a chair, of a base, a main lever pivoted to the base and extending in a direction from front to rear of the chair, a cross lever pivoted at each end of the main lever and disposed transversely of the chair, the chair being attached to the ends of the cross levers.

10 15 Signed at New York, N. Y., this twenty-fifth day of July, 1929.

FREDERICK D. W. SEARING.
